UNITED STATES PATENT OFFICE.

WARREN S. JOHNSON, OF MILWAUKEE, WISCONSIN.

MECHANICAL MOVEMENT.

SPECIFICATION forming part of Letters Patent No. 542,708, dated July 16, 1895.

Application filed February 8, 1895. Serial No. 537,689. (No model.)

To all whom it may concern:

Be it known that I, WARREN S. JOHNSON, a citizen of the United States, residing at Milwaukee, in the county of Milwaukee and State of Wisconsin, have invented certain new and useful Improvements in Mechanical Movements, of which the following is a specification.

This invention consists in a novel mechanism or "mechanical movement" designed to convert or translate a relatively slow and gradual movement into a quick or sudden movement.

The mechanism is susceptible of various applications, such as adjusting-signals, moving valves and dampers, shifting-clutches, operating photographic camera-shutters, and the like, and my purpose is to claim the mechanism broadly and apart from any other structure or device, and to make and sell the same, either as a device complete in itself or to combine it with other parts, as may be found desirable in practice.

In the accompanying drawings, Figure 1 is a perspective view of my new movement in a form suited to the control of valves and other like devices; Fig. 2, a vertical sectional view of the same, and Fig. 3 a side elevation of the device slightly modified in regard to the actuating-motor.

In many situations it is desirable or even essential to the attainment of a given result that one part or device be given a sudden throw from one to the other limit of its range of movement. On the other hand, it is often the case that the only available or convenient prime motor for imparting motion to such part or device is a slowly-acting motor, such as a piston, moving within a cylinder to which fluid under pressure is admitted quite slowly or a lever actuated by a float in a tank of considerable capacity. Under such circumstances an intermediate mechanism or translating device becomes desirable or even essential, and to meet this requirement is the purpose of the present invention.

It is to be understood that so far as the part to be actuated or controlled and so far as the particular prime motor are concerned, the embodiment of my invention here represented is merely typical or illustrative, these

matters being variable at will or as circumstances require.

Referring now to the drawings, A indicates a base or back plate designed to carry the various parts of the mechanism.

B indicates a yoke or forked bracket, to the arms of which is pivoted a frame C, here represented as extending upward in a substantially-vertical plane above the pivot-rod a. An arm b extends downward below the pivot-rod a, and is provided with a stud c to enter one end of a spiral spring D, the opposite end of which rests against an adjustable nut E, screwed upon a threaded stem or post F, projecting from the back plate A.

The spring D tends to throw the upper end of frame C inward or toward the back plate A with a force dependent upon the adjustment of nut E.

G G' is a toggle, the upper member G of which is pivotally carried by a cross-rod d at or near the upper end of swinging frame C. The lower member G' of the toggle carries a cross-rod e, the ends of which are shouldered or reduced and extend into slots or elongated openings f in the side bars of frame C.

H H indicate two helical springs, each attached at one end to cross-rod d and at the other end to cross-rod e, and tending constantly to draw the latter toward the former.

From what has been stated it will be seen that when the toggle G G' is straightened, so that the pivot or joint connecting its two members is in alignment with the cross-rods d and e, said rods will be separated to the greatest distance practicable, and the springs H H will be elongated and put under the greatest tension possible under the described arrangement of parts. It also follows that if the joint or pivot g of the toggle passes to either side of a straight line connecting the cross-rods d e the springs H H will immediately draw the cross-rod e toward the cross-rod a, and thereby bend or bow the toggle until the tension of the springs is taken up or a stop is encountered.

The upper member G of the toggle is extended above or beyond the axis of its pivot d and is preferably fashioned into a fork j, as shown in Fig. 1, the arms of which are provided with inwardly-projecting studs, as

shown. These studs enter a circumferential groove in a block or nut I, carried by a rod or stem J, which is guided in a neck or boss projecting from back plate A and is capable of 5 a limited longitudinal movement.

In the drawings I have represented rod J as provided with a boss or stop h to limit the movement of the rod in one direction, its reverse movement being restricted by the nut 10 I. By adjusting the nut upon the rod J the range or extent of movement of the rod can be regulated and determined.

Rod J may connect in any convenient manner with or may be an integral part of the device or member requiring the quick throw, and, in fact, is often made the stem of a valve. 15

The throw or play of frame C is regulated and determined by stop-nuts K and L, screwed upon a threaded post or stem M, projecting 20 from the back plate A, as shown in the several figures.

For the purpose of actuating the device I have represented in Figs. 1 and 2, a convex disk or head N, carried by frame C, and resting upon a flexible diaphragm O, constituting one wall of a fluid-pressure chamber P. Chamber P is supplied with fluid or liquid under pressure, which enters by a quite restricted passage i, and consequently the filling 25 of the chamber is gradual and the movement of head N and frame C produced by the fluid-pressure behind the diaphragm O will likewise be gradual or comparatively slow. The same is true where a cylinder and piston are substituted for the flexible diaphragm, as in Fig. 3, and so, of many other actuating devices that may be employed.

Assuming that the parts be in the position indicated in Figs. 1 and 3, which is the position they assume when no force is acting upon frame C to throw it outward, the rod or stem J, being then at the limit of its outward movement and stopped by the boss h, forms a fixed bearing or abutment, against which the fork j of toggle G G' bears. If, now, outward pressure be applied to the frame C by admission of fluid to chamber P, or otherwise, the fork j cannot move with frame C. Hence the upper member G of the toggle will rock or tip 45 upon its pivot d, thereby causing joint g of the toggle to move to and to pass the plane of pivots d and e. In thus moving to and until carried just beyond this plane the toggle G G' extends springs H H, but the instant 50 that plane is passed said springs contract, draw the cross-rod e upward, and bow the toggle outward, as in Fig. 2, and, in doing so, throw the fork j quickly inward to the full limit of movement permitted by nut or block I. Thus 55 a very gradual movement of the frame C and of the motor which actuates it is translated into a quick and positive movement of the stem J and of any part formed with or carried by it. On the other hand, if the stem I be at 60 the inner limit of its throw or movement, as in Fig. 2, in which case the nut I will bear

against the end of the guiding-boss of stem J, the yoke or fork j will bear against the nut and be thereby held at rest. If, now, the fluid within chamber P be allowed to escape slowly, 70 the spring D, acting upon frame C, will gradually swing it inward to the position indicated in Fig. 2, but as the fork j is prevented by the nut I from moving bodily inward with the frame the member G of the toggle will be 75 caused to rock upon its pivot d and to swing the two members of the toggle into line and then past the plane of pivots d e. When this plane is passed the toggle will be quickly bowed inward, and stem J will be thrown suddenly outward to the limit of its movement. Precisely the same action takes place when a cylinder and piston are employed, as in Fig. 3.

While I have represented the stem J as provided with a stop h and the nut I as arranged 85 to bear against the end of the neck or boss in which stem J is guided, it is to be understood that these are merely typical or illustrative of stops generally, which may be applied to any part connected with stem J. 90

The dimensions and the relative proportions of parts, their shape, or configuration and like matters may be varied as desired without departing from the spirit and scope of my invention. The yoke j may be replaced 95 by any equivalent means of connection.

Having thus described my invention, what I claim is—

1. A mechanical movement comprising the following elements in combination: a swinging frame; means for moving said frame; a toggle carried by said frame and having one member pivoted and the other arranged to slide therein; a device to be moved; a connection between the toggle and said device; and a spring connected with and serving to bow the toggle. 100

2. In combination with a movable device as J, provided with stops to determine its range of movement, mechanism for imparting a sudden movement thereto in opposite directions, consisting of a swinging frame, means for moving said frame, a toggle having one member pivotally attached to and the other arranged to slide in said frame, a spring connected with and tending to bow the toggle, and a connection between the toggle and the device to be moved, substantially as set forth. 110

3. In combination with a movable device as J, having a restricted range of movement, 115 mechanism for moving the same suddenly in one and the other direction, consisting of a swinging frame, a motor for moving said frame, a toggle having one of its members pivoted in said frame and connected with the part to be moved, and having its other member arranged to slide in the swinging frame, and a spring connected with and serving to bow the toggle. 120

4. In combination with a member having a restricted range of movement, as J, and with a prime motor as N, O, P, a translating device 130

interposed between the member to be moved and the motor, and comprising a swinging frame C, a toggle G G' carried therein by pivotal connection d and sliding connection e, a yoke j extending from the toggle to the member to be moved, and a spring H connected with and serving to bow the toggle when its three pivots are thrown out of alignment.

5. In combination with a member as J, having a restricted range of movement, a swinging frame C, stops to limit the play of said frame, a motor for moving said frame in one direction, a spring for returning said frame,

a toggle carried by said frame and having its members respectively connected therewith by 15 pivotal and by sliding connections, a spring acting upon and serving to bow the toggle, and a connection between the toggle and the member to be moved.

In witness whereof I hereunto set my hand 20 in the presence of two witnesses.

WARREN S. JOHNSON.
